(57) **CLAIM**

We claim the ornamental design for a combined garden cart and bucket holder, as shown and described.

DESCRIPTION

FIG. 1 is a front perspective view of a combined garden cart and bucket holder of the claimed design.

FIG. 2 is a right side elevation view of the claimed design.

FIG. 3 is a top view of the claimed design.

FIG. 4 is a bottom view of the claimed design.

FIG. 5 is a front elevation view of the claimed design; and,

FIG. 6 is a back elevation view of the claimed design. The ornamental design which is claimed is shown in solid lines in the drawings. The broken lines in the drawings are for illustrative purposes only and form no part of the claimed design.

The broken line showing of the handle, areas of the cart and wheels are to shown elements of the cart that are not part of the claimed design.

The broken line segments in the bucket holder area are intended to represent a unspecified depth of the bucket holder area.
